UNITED STATES PATENT OFFICE.

ELMER C. POOL, OF NEW CASTLE, PENNSYLVANIA.

FEED MECHANISM.

Application filed May 28, 1921. Serial No. 473,461.

To all whom it may concern:

Be it known that I, ELMER C. POOL, a citizen of the United States, and resident of New Castle, in the county of Lawrence and State of Pennsylvania, have invented certain new and useful Improvements in Feed Mechanisms, of which the following is a specification.

This invention is a continuation in part 10 of the invention described in my application filed November 26, 1920, having Serial No. 426,627, and relates to the manipulation of sheet metal plates, and more particularly to the feeding of such plates, one at a time, 15 from a pile to a tinning machine, and has for one of its objects the producing of an improved feeding mechanism whereby a vacuum cup roller will be employed to lift the plates, one at a time, from a pile, without moving more than one plate, and without disturbing the position of the plate or plates next to the one being moved.

Another object of this invention is to provide a friction roller having vacuum cup 25 projections thereon adapted to adhesively engage the face of the plate without the aid of a suction or vacuum producing device.

The above and other objects and advantages will be more fully brought out in the 30 following specification and claims, and will be fully illustrated in the accompanying drawings, in which—

Figure 1 is a sectional side elevation of the device.

Figure 2 is a top plan thereof.

Figure 3 is a rear elevation thereof.

Figure 4 is a side elevation showing the driving connections.

Figure 5 is an enlarged detail view of the 40 feed roller partly in section.

Figure 6 is a cross sectional elevation on the line VI—VI of Figure 5.

In the accompanying drawings, the letter A designates a tinning pot, in itself an old 45 and approved form. The pot is separated transversely by a vertical wall or partition 2, into compartments B and C. The lower edge of this partition or septum 2 which terminates above the bottom of the tinning 50 pot, and the upper edge of a rib or projection 3 on the bottom of the pot defines the width or vertical dimensions of a narrow passage or opening D, through which the plates, while submerged in the bath of molten tin, pass from the compartment B 55 into the compartment C of the pot A. The

particular pot shown is of a width which permits of two or more plates, side by side, being passed through the tinning pot.

Located immediately above the upper edge of the compartment B, at the plate entering side of the tinning pot, are two sets of feed rollers E and F, which are arranged to receive the plates from my improved feeding mechanism to be described, 60 and to move them forwardly and downwardly into the tin pot at an angle to the horizontal.

The feed rollers F are at a somewhat lower level than the rollers E, and an adjustable roller G is located on the discharge side of the set F to guide and direct the front end of the successive plates forwardly and downwardly and into the molten tin in compartment B, as they emerge from between the rollers F.

Positioned within the compartment B, closely adjacent to the passage D, is a set of pressure rolls I. These pressure rolls feed the plates from compartment B into 70 the compartment C.

Two sets of feed-out rollers J and K are provided in the compartment C of pot A to feed-out the plates and also to squeeze off surplus tin from the plates.

An inclined apron plate 10 is provided at the entrance end of the compartment B of the pot to receive the plates as they are delivered from my improved feeding mechanism. Other guide plates 12 and 13, are arranged to guide the plates to the rolls F and I, and curved guide plates 14 and 14' form a guide N which directs the forward end of the plates emerging from the set of pressure rolls I upwardly into the bite of the lower set J of the feed-out rollers J and K.

My improved feeding mechanism as shown is adapted to be located directly to the rear of the tinning pot and comprises a double 100 set of parts arranged side by side so as to act on two piles of plates at one time, thereby feeding two plates, side by side, into the tinning machine.

A framework or supporting structure 16 is 105 secured to and extends rearwardly from the tinning pot A and supports the several parts comprising my feeding mechanism. A bosh or receptacle 17, secured to and extending below the framework 16, is adapted to contain a vertically adjustable plate pile holder. The plate holder comprises a back rest mem-

ber 19 which is secured to the back wall of the bosh 17 and projects inwardly and downwardly on an angle, so as to slidably support an L-shaped plate retainer 20 which is of sufficient width to hold two piles of plates side by side. The plate retainer 20 is adjustably held in position and adapted to be vertically adjusted by means of a pair of chains 21, one of which is secured on each 10 end and thereof and passed upwardly over suitable sheaves 22 splined on a shaft 23. This shaft is journaled in the bosh and a ratchet and dog operating mechanism 24 is provided on one end outside of the end wall 15 of the bosh.

Mounted on the rear edge of the supporting framework 16 at each end and at the center thereof is a bracket 25 supporting a shaft 26, the shaft having four arms 27 loosely 20 mounted thereon for pivotal movement.

The arms 27 have a pair of cylindrical vacuum cup rollers Y journaled and supported in their lower ends, and the center arms have their upper ends counterweighted 25 by adjustable counterweights 29 mounted on a projecting arm 30. A locking lever 31 is pivoted on the arms 27, having the counterweights adjacent their upper ends, and such lever is provided with a notch 32 to 30 engage with the projecting tongue 33 on the frame 16 so as to hold the rollers Y out of their plate engaging position when desired.

The vacuum cup lifting rollers Y are somewhat similar to the well known vacuum 35 cup pneumatic tire, each comprising a cylindrical hollow body 34 of metal having bearings 35 at each end, joined to the body by suitable spokes 36, and having an outer covering 38 of elastic material, such as rubber, which is provided with a series of closed 40 vacuum cups or projections 39, having concave faces forming adhesive members adapted to engage and adhere to the plates to be lifted.

45 The projections 39 are preferably arranged in rows and the projections of one row are staggered with relation to those of the next row. The projections or vacuum cups 39 are different from the ordinary suction cups employed to feed paper, etc., in that they are closed cups and need no suction or vacuum producing device to cause the plates to adhere to them. On the contrary they are formed of sufficiently resilient or 50 elastic material that they will compress against the plate and force the air from their hollow faces and adhere to the plates rather than have the plates sucked up against them.

60 The rollers Y are mounted in pairs on shafts 37 journaled in suitable bearings formed in the lower ends of the arms 27, and are adapted to be rotated by means hereinafter described.

65 It will readily be seen that as the rollers

Y are rotated, the rows of vacuum cup projections 39 will successively engage the outermost plate of the pack in the container 20, thus adhering to the plate and moving it upwardly. 70

Suitable cross-beams 40—40' are arranged from one end of the frame support 16 to the other immediately above the upper edge of the bosh, and carry suitable curved guide strips 41—42 arranged to form an upwardly and inwardly inclined passageway to guide the plates being conveyed. 75

A second pair of cross-beams 43—43' is arranged forward and above the cross-beams 40, and carry other guide strips 44—45 forming a second passage-way adapted to receive the plates from the passage-way between the strips 41—42, and direct them forwardly and upwardly between suitable pinch rollers 46 and 47 of any well-known 80 construction. 85

The lower one of the pair of pinch rollers E is driven by a suitable source of power and carries a sprocket 48 on each end. The pinch roller 46 also carries a sprocket 48^a 90 on each end in line with the sprocket 48, and a third sprocket 48^b is mounted on each end of the shaft 26 in line with the sprockets 48 and 48^a. A link chain 49 is trained over the sprockets 48, 48^a, 48^b, thus driving the 95 pinch rollers E, pinch rollers 46 and 47, and shaft 26 at the same speed. It will be understood that if found desirable in practice, a single set of drive sprockets may be used.

A pair of sprockets 50 of somewhat smaller 100 diameter than the sprockets 48^a, 48^b are mounted on the ends of the shaft 26, and a sprocket 51, of greater diameter than sprockets 50, is mounted on the outside end of the shafts 37, and a link chain 52 is trained over the sprockets 50 and 51 to constantly drive the conveyer members, which will necessarily revolve at a lesser speed than the pinch rollers E and pinch rollers 46, 47, due to the difference in size of the sprockets 50 and 51. 110

A cross-beam member 54 is arranged forward of the rollers 46—47 and has two pairs of suitably spaced depending lugs 55 which support pivot rods or shafts 56 adapted to have guide plates 57 hingedly supported thereon. Plates 57 have a crank arm 58 secured thereto which abuts the cross-beam 54 when the plate is in its lowermost position, and carries a counterweighted lever 59 to normally hold it in such position. 115

Supported on suitable cross-beams 60 forward of the hinged plates 57, and in proximity thereto, is a pair of guide plates 61. The plates 61 are formed of top and bottom pointed portions, the top portions being directed forwardly over the rollers E and the bottom portion directed downwardly and forwardly to the passage between the rollers E. 125

The inclined apron 10 of the tinning pot 130

is arranged below the plates 57 and 61, and completes the passage-way to the rollers E.

The hinged counterweighted guide plates 57 serve as a trap so that if more than one plate or sheet should be carried through the pinch rollers 46-47 their tension will be a sufficient bearing against the guide plate 57 to counteract the counterweighted lever 59 and raise the guide plate, thereby allowing the plurality of feed plates or sheets to pass over the dual guide plates 61 and away from the tinning pot.

Magnetic separators X are mounted above each of the rollers Y and comprise a rectangular casing member 63 pivotally supported on the cross-beam 40. The casing 63 contains a permanent magnet 64 and is provided with blades or knife edge poles 65 which extend into the path of the lifted plates and contact with the rear faces thereof. The magnet 64 has less adhering power than the plate lifter Y, and, therefore, will not materially retard the movement of the plates, yet it is of sufficient strength that if two plates should stick or in some manner be lifted together, it will retard the movement of the second plate and thus separate them.

A still further means for preventing the feeding of more than a single plate into the tinning pot is located just to the rear of the pinch rollers 46-47, and comprises a shaft 67 journaled in the frame support 16 and having a plurality of locking fingers 68 of triangular shape secured thereon, and of such size that their flat sides will extend past the guide strips and into the path of the lifted plates. The plates, as guided between the strips 44 and 45, will bear against the upper strips 45 due to the direction of their travel, and in this position they will strike the fingers 68 and cause the shaft and fingers to rotate one-third of a revolution; thereby presenting one of the other faces of the fingers against the plate. If a second plate is overlapped on the first in such a manner that its forward edge is disposed to the rear of the forward edge of the first plate, it will strike the fingers and be held, since the fingers cannot again rotate until the first plate has passed from under and is clear of the fingers.

Another feature and function of these fingers is that they will cause an even feed of the plates from both of the feed rollers Y, since if one roller feeds a plate in advance of the other, the first to reach or strike the fingers 68 will rotate them the one-third turn, and then lock them against rotation until it has passed from thereunder, and the plate that is in the rear will be held until the fingers are again freed when another plate will be presented by the other feed roller to follow the one just clearing the fingers, thus causing the newly presented plate,

and the held plate, to pass together to the rollers 46-47.

The operation of my improved feeding mechanism will be readily understood from the above description taken with the accompanying drawings. The peculiar and novel construction of the lifting rolls will cause the automatic feeding of single plates without the use of suction or vacuum producing devices, the plates being fed through the guide passages to the pinch rollers 46-47, which will in turn feed it to the pinch rollers E of the tinning pot.

The operation of the three separate mechanisms for preventing more than one plate so being carried to the tinning pot, have also been fully described above, and will not be gone into again, although these mechanisms are important features and are distinct improvements over any devices heretofore known.

It will be readily understood that while I have described my invention in combination with a tinning pot, it is not limited to such use, but may be used wherever it is desired to feed single plates, and therefore I do not wish to be limited to such a combination.

It will also be understood that while I have shown and described one embodiment of my invention with great particularity, I do not wish nor do I intend to limit my invention to such structure, since various modifications in structure and combination of parts may be made without departing from the spirit of my invention as defined in the appended claims. For instance, modified forms of the lifting rollers Y may be used, wound active magnets may be substituted for the permanent magnets shown, or other such substitutions of equivalents made as found necessary or desirable.

It will also be further understood that this apparatus may be used to feed plates from a horizontal pile. That is, the plates may be moved longitudinally or sidewise from a horizontal pile, and the words lifted, or lifting, as used in the several claims will be understood to include this movement.

I claim:—

1. Plate feeding means comprising a rotary plate feeding member, said member having a plurality of closed vacuum cups on its surface adapted to adhesively engage a plate, and means for rotating said feeding member in the plate feeding operations.

2. An automatic plate feeder for lifting and feeding single plates from a pile, comprising a rotary plate feeding member having a plurality of projections arranged in radial rows around its periphery, said projections being provided with cupped faces for adhesively engaging the exposed face

120
125
130

of the outermost plate as the feeding member is rotated, and means for rotating said member.

3. The combination with a tinning pot, 5 of a rotary plate feeding member having a plurality of closed vacuum cups arranged in radial rows around its periphery, said feeding member operating to move plates one by one from a pile in which the plates bear 10 one against the other.

4. The combination with a tinning machine for tinning metal plates, and a support for a pile of plates to be delivered to the machine with the plates of the pile in 15 facewise engagement one with the other, of a rotary plate feeding member having a plurality of closed vacuum cups projecting from its face and arranged in rows disposed diametrically around its periphery, said 20 rows of cups being adapted to successively engage the exposed face of the outermost plate as the feeding member is rotated, said feeding member operating to move plates one by one from said pile.

25 5. A rotary plate feeding member comprising a cylindrical non-yielding body

portion, an outer covering of yielding material secured around the periphery of said non-yielding body portion, and a series of closed vacuum cups formed on said yielding 30 covering adapted to adhesively engage the plate to be fed.

6. A rotary plate feeding member comprising a cylindrical non-yielding body portion, an outer covering of yielding material 35 secured around the periphery of said non-yielding body portion, and a series of closed vacuum cups projecting from the face of said yielding covering and arranged in rows disposed diametrically around the periphery 40 of said feeding member, said rows of cups being adapted to successively engage the plate to be fed.

7. A rotary feeding member comprising a cylindrical yielding body portion, and a 45 series of closed vacuum cups arranged around its periphery adapted to engage and adhesively grip a plate to be fed without the aid of a vacuum producing device.

In testimony whereof I have hereunto 50 signed my name.

ELMER C. POOL.
